CLAIM

The ornamental design for a pump dispenser, as shown and described.

DESCRIPTION

FIG. 1 is a front, right side, bottom perspective view of a pump dispenser showing my new design thereof;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a reference cross-sectional view thereof, taken in the direction of line 8-8 of FIG. 2; and,

FIG. 9 is a reference view thereof, showing a state in which this article is used.

The broken lines in the drawings and the areas within them depict portions for a pump dispenser that form no part of the
